UNITED STATES PATENT OFFICE.

OTTO JOHNE, OF BAUTZEN, GERMANY, ASSIGNOR TO BAUTZNER INDUSTRIEWERK, AKTIENGESELLSCHAFT, OF BAUTZEN, GERMANY, A FIRM.

MACHINE FOR CUTTING PILES OF PAPER.

1,150,602.

Specification of Letters Patent. Patented Aug. 17, 1915.

Application filed January 8, 1914. Serial No. 811,044.

To all whom it may concern:

Be it known that I, OTTO JOHNE, engineer, a citizen of the German Empire, residing at Bautzen, Germany, have invented certain new and useful Improvements in Machines for Cutting Piles of Paper and the like, of which the following is a specification.

This invention is an improvement in, or modification of, the invention described in the specification filed with my application for Letters Patent Serial No. 762,657 of April 21, 1913. In this machine the clamp springs are arranged in such a manner that when the clamp or press beam occupies its highest position, they are not under tension or compression, but that when this beam bears upon the pile of paper, and before the knife commences its cut, they have already received their highest compression.

According to my present invention, the press springs are pivoted at one end to a fixed pivot and at the other end to a lever which is connected with levers for moving the press beam through the agency of a toggle joint actuated by crank gear.

The device described in my prior specification cited can only be used for cutting machines in which the connecting rods engage the two longitudinal ends of the knife beam and exert traction upon it in a direction perpendicular or partially perpendicular to the direction in which the knife beam is displaced. It is not possible to employ that device, without modification, in what are termed "wheel" cutting machines. It is precisely this type of machine, however, that is most convenient, simple and economical. The only defect presented by this class of machine as hitherto constructed is that it was impossible to incorporate with them an automatic clamping mechanism certain in its operation and suitable for high-speed power machines.

In particular difficulty was experienced in causing the clamping mechanism with piles of different heights to act automatically before the cutting begins.

Now in accordance with the present invention the automatic clamping mechanism described in my prior specification is also applicable to "wheel" cutting machines, that is to say to machines in which the tension rods act either approximately at the

middle or at the end of the knife beam and in which moreover, the tractional effort exerted by these rods approximately coincides with the direction of displacement of the knife beam.

The invention is illustrated in the accompanying drawings, in which:

Figure 1 is a front elevation thereof, and Fig. 2 is a side elevation.

The drive is from the pinion 25 onto the intermediate wheel 24; upon the same shaft as the latter is mounted the pinion 23, which meshes with the wheel 17 mounted on the shaft 16. Precisely like the crank disk 18, this wheel 17 comprises an eccentrically mounted stud, which the operating rods 20 of the knife beam 21 engage in the known manner. The shaft 16 also carries the wheel 22, which meshes with the gear wheel 14 mounted on the crank 13 and produces the rotation of the latter. The link 15 connects the crank 13 with the toggle lever constituted by the compression rods 5 and 6, which is alternately collapsed and extended by the reciprocating movement of the link 15. At its upper end the rod 6 is pivoted to the bell-crank lever 7. The tension rod 8 connects the bell-crank levers 7 and 9, with which the compression rods 10 and 11 are connected, thus effecting the connection with the press beam.

The compression rod 5 engages the bell-crank lever 3 at the point 4. On the other eye of this lever the press spring is arranged, its other end bearing against the fixed pivot 2.

The operation and the position of the wheels 22 and 14 relatively to each other are the same as described in my prior specification cited. The press springs 1 are tensionless when the knife occupies its highest position, but before the knife reaches the pile of paper, compression takes place until the toggle 5 and 6 is extended and the press springs are given their tension, and remain in tension during the cutting operation.

In the embodiment of the invention herein illustrated, a single toggle is employed for the displacement of the press beam on the one hand and for tensioning the springs on the other hand. The toggle joint simultaneously transmits the tension of the spring to the press beam. The toggle joint is operated in the same manner as the spring

pressure mechanism and the press beam in the main patent.

The toggle joint can be sub-divided constructionally into separate bell-crank levers, the drive of which may be separate but kinematically connected.

Having now particularly described and ascertained the nature of my said invention and in what manner the same is to be performed, I declare that what I claim is:

1. In wheel operated paper cutting machines of the character described, in combination with the cutter thereof, an automatic paper presser, a spring for actuating said presser, a lever to which one end of said actuating spring is fastened, a fixed pivot for securing the other end of said spring, means for operating the presser beam, means for connecting said means with said lever, and means for actuating said means connecting the lever with said means for operating the presser beam, for displacing said presser beam and tensioning the spring in-

dependently of the cutter, substantially as described.

2. In wheel operated paper cutting machines of the character described, in combination with the cutter thereof, an automatic, spring actuated paper presser, a lever to which one end of said actuating spring is fastened, a fixed pivot for securing the other end of said spring, levers for operating the presser beam, a toggle joint connecting said levers with said first named lever, and a crank gear for actuating said toggle joint for displacing the presser beam and tensioning the spring independently of the cutter, substantially as described.

In testimony whereof I have hereunto set my hand in presence of two subscribing witnesses.

OTTO JOHNE.
